Air Brake Company, Wilmerding, Pa., a cor-
poration of Pennsylvania

Application October 29, 1938, Serial No. 237,679
In France March 7, 1938

11 Claims. (Cl. 121—164)

This invention relates to control devices for horns or the like actuated by fluid under pressure and more particularly to a device of this character for controlling the operation of horn or warning signal apparatus comprising two horns of different acoustic pitch which are to be rendered operative alternately so as to emit two different notes in succession and in continuous repetition while the control device is actuated.

10 The invention has for its object to provide an improved control device for this purpose which is of simple and compact construction and relatively cheap to manufacture.

According to one feature of the invention the 15 supply of fluid under pressure to the two different horns or the like alternately is arranged to be effected by the action of the fluid supplied to a motor mechanism comprising a number of pistons or other movable abutments of the same 20 effective area.

According to another feature of the invention the order and duration of the supply of fluid to the two horn devices and the intervening interval is arranged to be invariable and predetermined so that the composite warning note emitted 25 possesses a constant character regardless of the manner in which the control device is actuated by the operator.

The invention is illustrated in the accompanying 30 drawing the single figure of which is a view in sectional elevation of one form of control device embodying the invention.

Referring now to the drawing it will be seen that the device comprises a casing or body 1 having a chamber 2 in permanent communication with a suitable source of fluid under pressure through a supply pipe 3. One end of the chamber 2 is constituted by a piston 4 suitably secured to one end of a sleeve-like piston rod 5, 35 the upper end of which is similarly secured to an oppositely disposed piston 6 of the same diameter as piston 4 and adapted to move in a cylinder formed within the casing 1.

The piston rod 5 is surrounded by a relatively 40 movable collar 7 between which and the piston 4 a spring 8 is interposed. The collar 7 is normally urged into engagement with an annular flange 7a provided on the piston rod 5 and is adapted to be displaced in a direction away 45 from said flange by means of an arm 9 extending from a control lever 10 which is pivotally mounted on a pivot pin 11 secured in the casing 1.

The upper part of the casing 1 contains a 50 piston 12 of the same construction and diameter

as the pistons 4 and 6 and provided with a downwardly extending tubular stem 13 the interior of which communicates at its upper end with a chamber 14 formed between the pistons 6 and 12 and at its lower end with the chamber 2. A control spring 15 is located in a chamber 16 above the piston 12, this spring being interposed between the piston 12 and the upper end of the casing 1.

The chamber 16 communicates with a passage 10 17 formed in the casing 1 and leading to upper and lower ports 18 and 19 formed in the wall of the chamber 2, said ports being of such flow capacity as to provide the desired operation of the device to be later described. 15

A passage 20 in the casing 1 terminates in ports 21 and 22 formed in the cylindrical portion of the casing 1 containing the pistons 6 and 12. This portion of the casing is also provided with a port 23 communicating with a 20 pipe 24 leading to a horn or warning signal device (not shown) giving a relatively low pitched or bass note. Another port 25 in this portion of the casing 1 communicates with a pipe 26 leading to a second horn or warning signal device 25 (not shown) giving a relatively high pitched or treble note.

A suitable seal or stuffing box device 27 is provided for closing communication between a chamber 28 below the piston 6 and a chamber 29 30 in the casing 1 containing the collar 7, the latter chamber being open to the atmosphere. The stuffing box device 27 also acts in the capacity of a stop to be engaged by the flange 7a on piston rod 5 for defining the normal or non-operating position of the collar 7. 35

An external shoulder 30 formed on the piston stem 13 is adapted to co-operate with an internal shoulder 31 formed on the piston rod 5 as will be hereinafter explained, said stem and rod having 40 sliding contact with each other at opposite sides of said shoulders.

Operation

The parts of the device are shown in the drawing 45 in their normal or non-operating condition, in which compressed air supplied from any suitable source through the pipe 3 enters the chamber 2 and passing through the tubular stem 13 enters the chamber 14. Compressed air from the 50 chamber 2 also flows through the port 19 and passage 17 to the chamber 16. The chambers 2, 14 and 16 are thus all charged with fluid at the same pressure. The space 28 below the piston 6 is open to the atmosphere through the un- 55

covered port 25, pipe 26 and the treble horn (not shown), while port 23 is lapped by the piston 6, so that both horns (not shown) are thus silent.

5 When it is desired to give a warning signal the control lever 10 is rotated about its pivot 11 in the direction indicated by the arrows with the result that the arm 9 acting upon the collar 7 causes the latter to move downward. This 10 downward movement of the collar 7 is transmitted through the spring 8 to the piston 4 which accordingly moves downwardly carrying with it the piston rod 5 and the piston 6.

The downward movement of piston 6 uncovers 15 the port 23 so that compressed air from the chamber 14 is supplied through the port 23 and the pipe 24 to the bass horn (not shown). The downward movement of the piston 4 covers the port 19 and uncovers the port 18 so that communication 20 between the chambers 2 and 16 is cut off and the chamber 16 is vented to the atmosphere through the passage 17 and port 18. The piston 12 is then moved upwards by the pressure of fluid in the chamber 14 compressing the spring 15. This upward movement of the piston 12 uncovers the port 21 but the port 22 has previously 25 been covered by the downward movement of the piston 6, so that the chamber 28 is isolated.

30 During the upward movement of the piston 12 carrying with it the stem 13 the shoulder 30 engages with the shoulder 31 and the stem 13 thus causes the piston rod 5 and the pistons 4 and 6 to move upwardly compressing the spring 8. It 35 will be observed that the pressures in the chambers 2 and 14 being equal to one another and the areas of the pistons 4 and 6 being also equal the sleeve 5 is substantially balanced as regards the opposing fluid pressures in the chambers 2 and 40 14. The upward movement of the piston rod sleeve 5 is thus readily effected by the stem 13 and said sleeve and the pistons 4 and 6 are returned to their normal position shown, in which the ports 19, 22 and 25 are uncovered and the 45 ports 18 and 23 are covered. As a result of covering port 23 the bass horn (not shown) is silenced, while fluid under pressure is supplied from the chamber 28 to the treble horn (not shown) by way of port 25 and pipe 26, the chamber 28 being replenished with fluid from the chamber 14 through uncovered port 21, passage 50 20 and port 22.

The port 19 being uncovered upon upward movement of piston 4, fluid under pressure is 55 again supplied from the chamber 2 to chamber 16 through passage 17 so that the piston 12 is then moved downwardly under the action of the spring 15, thereby covering the port 21 and cutting off the supply of fluid from the chamber 60 14 to the chamber 28. The operation of the treble horn then ceases as soon as the fluid contained in the chamber 28 has become exhausted.

The pistons 4, 6 and 12 are thus all returned 65 to their original or normal positions, and if the control lever 10 and consequently collar 7 and spring 8 have been permitted to return to the position shown, the operation of the horns will cease as soon as the pressure in the chamber 28 has been reduced to atmospheric pressure by flow 70 of fluid to the treble horn.

If, however, the lever 10 is maintained in its operative position so as to continue to exert a downward pressure through the spring 8 upon the piston 4 by means of the collar 7, the pistons 4 and 6 will again be moved downwardly by

said spring upon the venting of fluid from chamber 28 and the cycle of operation above described will be continuously repeated, that is to say, the venting and reduction of pressure in the chamber 28 will cause the pistons 4 and 6 and the rod 5 again to move downwardly effecting the production of a note by the bass horn followed by the production of a note by the treble horn as these pistons again move upwardly.

It will be observed that the cycle of operation 10 above referred to invariably begins with the emission of a note by the bass horn and concludes with the emission of a note by the treble horn.

While one illustrative embodiment of the invention has been described in detail, it is not 15 the intention to limit its scope to that embodiment or otherwise than by the terms of the appended claims.

Having now described my invention, what I 20 claim as new and desire to secure by Letters Patent, is:

1. A reciprocatory motor comprising a control device adapted to be moved alternately first to one and then to another of two control positions, resilient means operative to effect movement of said control device from one of said positions to the other position, means for operating said resilient means, and a piston for moving said control device from said other position to said one position, said piston being controlled by said 30 control device and rendered operative in said other position and rendered non-operating in said one position.

2. A reciprocatory motor comprising a control device adapted to be moved alternately first to one and then to another of two control positions, 35 resilient means operative to effect movement of said control device from one of said positions to the other position, means for operating said resilient means, a piston operative by fluid under pressure for moving said control device from said other position to said one position, and means associated with said control device operative in said other position to render said piston effective to move said control device and operative in said one position to render said piston ineffective.

3. A reciprocatory motor comprising a control device adapted to be moved alternately first to one and then to another of two control positions, 50 resilient means operative to effect movement of said control device from one of said positions to the other position, manually operative means for conditioning said resilient means to move said control device, a piston having a connection with 55 said control device and operative by fluid under pressure upon movement of said control device to said other position for effecting movement of said control device to said one position, said control device in said one position balancing the fluid pressure on said piston for rendering same non-operative.

4. A reciprocatory motor comprising a control device having two control positions and adapted to be moved alternately first to one and then to the other of said positions, a spring connected to said control device, manually operative means for stressing said spring to move said control device from one of said positions to the other, a piston having an operating connection with said 70 control device and constantly subject to fluid pressure on one side and having a chamber at the opposite side supplied with fluid under pressure by said control device in said one position and vented by said control device in the said 75

other position, said piston being operative upon the venting of fluid under pressure from said chamber to move said control device from said other position to said one position.

5. A reciprocatory motor comprising a control device having two control positions and adapted to be moved alternately first to one and then to the other of said positions, a spring connected to said control device, manually operative means 10 for stressing said spring to move said control device from one of said positions to the other, a piston having a lost motion connection with said control device to permit relative movement of said control device from said one position to said 15 other position, said piston being constantly subject to pressure on one face and subject on the opposite face to variations in fluid pressure in a chamber, said control device being operative in said one position to supply fluid under pressure 20 to said chamber for balancing the pressures on said piston and being operative upon movement to said other position to vent said chamber whereby the pressure on said opposite face of said piston is rendered effective to operate said 25 piston to move said control device to said one position against the stress of said spring.

6. A reciprocatory motor comprising a control device adapted to be moved alternately first to one and then to another of two control positions, resilient means operative to effect movement of said control device from one of said positions to the other position, means for operating said resilient means, a piston for moving said control device from said other position to said 35 one position, said piston being controlled by said control device and rendered operative in said other position and non-operating in said one position, arresting means associated with said control device and controlled by the cooperative action of said piston and control device upon movement of said control device to said one position for holding said control device against movement out of said one position by said resilient means, and means for rendering said arresting means ineffective an interval of time after being rendered effective.

7. A reciprocatory motor comprising a control device adapted to be moved alternately first to one and then to another of two control positions, said control device being operative in said one position to supply fluid under pressure to a chamber and in the other position to vent fluid under pressure from said chamber, resilient pressure exerting means connected to said control device and operative to exert a pressure thereon for moving said control device from said one position to said other position, a piston having a lost motion connection with said control device and subject to the opposing pressures in said chamber and a constantly acting pressure and operative upon said chamber being vented to move said control device from said other position to said one position, means associated with said piston and cooperative with said control device upon obtaining said one position to supply fluid under pressure to another chamber for opposing the action of said resilient means, means operative upon charging the first named chamber with fluid under pressure for moving said piston relative to said control device for cutting off the supply of fluid under pressure to the second named chamber, and means for releasing the fluid under pressure from the second named chamber to condition said control device for movement by said resilient means.

8. A reciprocatory motor comprising a pair of spaced connected pistons of the same area and subject on opposite faces to the pressure of fluid from a source, said pistons being movable alternately first to one and then to another of two control positions, a spring arranged to act on one of said pistons and operative upon being stressed to effect movement of said pistons from one of said two control positions to the other, a third piston operatively connected to said pair of pistons and subject on one face to the pressure of fluid from said source and on the opposite face to the fluid pressure in a chamber, said pair of pistons being operative in said one position to connect said chamber with said source of fluid pressure for balancing the fluid pressures on said third piston for thereby rendering said resilient means effective to move said pair of pistons from said one position to said other position, and said pair of pistons being operative in said other position to vent fluid under pressure from said chamber to render said third piston effective to move said pair of pistons from said other position to said one position.

9. A reciprocatory motor comprising a pair of spaced connected pistons of the same area and subject on opposite faces to the pressure of fluid from a source, said pistons being movable alternately first to one and then to another of two control positions, a spring arranged to act on one of said pistons and operative upon being stressed to effect movement of said pistons from one of said two control positions to the other, a third piston operatively connected to said pair of pistons adapted to be operated by fluid under pressure to move said pair of pistons from said other position to said one position, said pair of pistons controlling the fluid pressure on said third piston for rendering said third piston effective upon movement of said pair of pistons to 40 said other position and ineffective upon movement of said pair of pistons to said one position.

10. A reciprocatory motor comprising a pair of spaced connected pistons of the same area and subject on opposite faces to the pressure of fluid from a source, said pistons being movable alternately first to one and then to another of two control positions, a spring arranged to act on one of said pistons and operative upon being stressed to effect movement of said pistons from one of said two control positions to the other, a third piston having a lost motion connection with said pair of pistons and adapted to be moved by fluid under pressure from a normal position to effect movement of said pair of pistons from said other position to said one position, a spring acting on said third piston for effecting movement thereof in the reverse direction relative to said pair of pistons back to said normal position, said pair of pistons controlling the fluid pressure on said third piston and being operative in said other position to render the fluid pressure on said third piston effective to move said pair of pistons and operative in said one position to balance the fluid pressure on said third piston to render said 60 spring effective, and means controlled by the cooperation of one of said pair of pistons and said third piston upon movement of said pair of pistons to said one position and the subsequent relative movement of said third piston to delay 70 movement of said pair of pistons by said resilient means.

11. A reciprocatory motor comprising a casing having a pair of axially aligned piston bores of the same diameter one of which bores is open 75

at its outer end to a third, coaxial piston bore, a control piston slidably mounted in each of the bores of same diameter, and a reversing piston slidably mounted in the third bore, a sleeve-like piston rod operatively connecting the two control pistons, a rod connected to said reversing piston and slidably mounted in said sleeve-like rod and having an axial passage connecting the chamber intermediate the third piston and adjacent control piston to a chamber at the outer face of the other control piston, said chambers being constantly connected to a source of fluid pressure, said control pistons having two positions, a spring arranged to act upon stressing to move said control pistons from one of said two positions to the other, means associated with said casing for stressing said spring, said control pistons in said one position supplying fluid under pressure to a reversing chamber at the other face of said reversing piston for balancing the fluid pressures thereon for rendering said spring effec-

tive, and said control pistons in said other position venting the fluid pressure from said reversing chamber for rendering said third piston effective to move said control pistons from said other position to said one position, said casing having a communication opened by one of said control pistons and said reversing piston when said reversing piston moves sufficiently to position said control pistons in said one position through which fluid under pressure is adapted to be supplied to act in a chamber at the inner face of the inner control piston for opposing movement of said control pistons by said spring, and a spring in said reversing chamber operative upon the supply of fluid under pressure thereto to move said reversing piston relative to said control pistons for closing said communication, said casing having a vent passage open to the last named chamber for releasing fluid under pressure therefrom. 20

ANSELME NEVEU.
